UNITED STATES PATENT OFFICE

167,736

CHIMNEY

Mark Lawson Bowman, St. Louis, Mo., assignor
to International Oil Burner Co., St. Louis, Mo.

Application April 18, 1951, Serial No. 14,884

Term of patent 14 years

(Cl. D62—3)

To all whom it may concern:

Be it known that I, Mark L. Bowman, a citizen of the United States, residing in the city of St. Louis, in the State of Missouri, have invented a new, original, and ornamental Design for a Chimney, of which the following is a specification, reference being had to the accompanying drawing, forming part thereof.

Figure 1 is a side view of a chimney, showing my new design; and

Figure 2 is a top plan view thereof.

I claim:

The ornamental design for a chimney, as shown.

MARK LAWSON BOWMAN.
